DESIGN FOR A BRACELET CHAIN

Saul Ritter, New York, N. Y.

Application October 27, 1937, Serial No. 72,457

Term of patent 3½ years

To all whom it may concern:

Be it known that I, Saul Ritter, a citizen of the United States, residing in New York city, in the county of New York and State of New York, have invented a new, original, and ornamental Design for a Bracelet Chain, of which the following is a specification, reference being had to the accompanying drawing, forming part thereof.

Fig. 1 is a plan view of a section of a bracelet chain showing my new design;

Fig. 2 is an edge view of the same.

I claim:

The ornamental design for a bracelet chain, as shown.

SAUL RITTER.
